(57) **CLAIM**

I claim the ornamental design for a drainage outlet, as shown and described.

DESCRIPTION

FIG. 1 is a top plan view of the present invention;
FIG. 2 is a front side view of the present invention;
FIG. 3 is a bottom plan view of the present invention;
FIG. 4 is a rear side view of the present invention;
FIG. 5 is a top perspective view of the present invention; and,
FIG. 6 is a bottom perspective view of the present invention. The broken line showing is included for the purpose of illustrating portions of the article and forms no part of the claimed design.
